UNITED STATES PATENT OFFICE.

JOHN J. MARCY, OF MERIDEN, CONNECTICUT, ASSIGNOR TO EDWARD MILLER, OF SAME PLACE.

DESIGN FOR A LANTERN.

Specification forming part of Design No. 1,549, dated March 18, 1862.

To all whom it may concern:

Be it known that I, JOHN J. MARCY, of Meriden, in the county of New Haven and State of Connecticut, have invented or produced a new and original Design for a Combined Hand Lamp and Lantern; and I do hereby declare that the following is a full, clear, and exact description of the same, reference being had to the accompanying drawing, making a part of this specification, said drawing being an elevation of my design.

A represents a hand-lamp, and B its handle, of annular form, attached to the side of the lamp. The body of this lamp is the base of the lantern when all the parts of the same are attached or connected together, and said body has its lower part formed of an ovolo a, above which there is a fillet b, said fillet being immediately below a cyma reversa c, which has a fillet d at its upper end. These moldings are inclined, so as to give the body of the lamp a conical form.

C is the glass protector of the lantern, which incloses and protects the flame. This protector is of cymatium form in its longitudinal section, and its base D, which is fitted on the top of the lamp A, is composed of an annular scalloped band e, having two fillets f g beneath it.

The glass protector C is surmounted by a cap E, the lower part h of which is a flat band having above it a quirk i, which is directly beneath a cylinder j, which is surmounted by an ovolo k.

F is the handle of the protector C, of oblong bail shape, as clearly shown in the drawing.

Having thus described my invention, what I claim as new, and desire to secure by Letters Patent, is—

The general configuration of the parts herein shown and described to form a new and original design for a combined hand lamp and lantern.

JOHN J. MARCY.
